The ornamental design for a lamp as shown and described.

DESCRIPTION

FIG. 1 is a perspective view of a lamp showing my new design;
 FIG. 2 is a first side view thereof;

FIG. 3 is a second side view thereof;

FIG. 4 is a front view thereof;

FIG. 5 is a rear view thereof;

FIG. 6 is a top view thereof; and,

FIG. 7 is a bottom view thereof.

The broken lines illustrate portions of the lamp that form no part of the claimed design. In FIG. 7, the area between the broken line circle and the adjacent concentric solid line circle, as well as the area within the broken line circle, forms no part of the claimed design.
